BLOWTORCH

Robert L. Livingston, Williamsport, Pa.

Application October 11, 1946, Serial No. 702,611

4 Claims. (Cl. 158—35)

1

This invention relates to improvements in blow torches. An object of the invention is the provision of a quick lighting and self-generating double duty blow torch in which a friction hinge is employed between a primer and a fuel tank carrying a combustion tube for regulating the position of the primer relative to the combustion tube for causing rapid ignition and combustion of the fuel, the flame from the primer being extinguished after the combustion tube is in operation.

Another object of the invention is the provision of an efficient blow torch in which a friction hinge is used for connecting a primer with a fuel tank in such a manner that the flame from the primer may be placed at any point along the combustion tube for igniting the fuel led to said tube by a wick and for pre-heating said tube, the arrangement being such that the body of the primer may be employed as a handle when the fuel tank becomes hot after long use.

A further object of the invention is the provision of a neat and compact blow torch having a fuel tank which will not leak when held in various positions and which may be filled in an upright position, wicks in the fuel and a priming tank being each housed in an internally threaded passage so that said wicks may be removed or replaced readily, a friction hinge connecting the fuel and priming tanks together so that the priming tank may place the flame of its wick in various positions along the combustion tube and a generator tube associated with the fuel tank, the wick in the fuel tank extending into the generator tube which projects into the combustion tube, the combustion tube being removable so that the generator tube may act as a double duty torch, the flame at the free end of the generator tube being maintained by the flame from the priming wick.

The invention consists in the novel construction, arrangement and combinations of parts hereinafter more particularly described and claimed.

In the drawings:

Figure 1 is a plan view of my blow torch.

Figure 2 is a side view in elevation of the torch with parts in section.

Figure 3 is a horizontal section through the priming tank and the fuel tank showing a connecting friction hinge.

Figure 4 is a horizontal section similar to that shown in Figure 3, but illustrating a modified form of friction hinge.

Figure 5 is a longitudinal vertical section of

the generator tube with the combustion tube attached.

Figure 6 is a view in elevation of the blow torch showing the combustion tube removed, and

Figure 7 is a view in elevation of the blow torch illustrating the operation of the priming tank in various positions relative to the combustion and generator tubes.

10 Referring more particularly to the drawings, 10 designates a fuel tank which is closed by a cover 11. A wick tube 12 inclined at an acute angle to the cover is sealed in an opening 12' in said cover with an open end 13 projecting into 15 the tank. A wick 14 has a portion in the tube and a portion 15 extending downwardly into the fuel in the tank. The upper outer portion 16 of the wick is disposed within a generator tube 17.

The outer free end of the tube 12 is threaded 20 (Fig. 5) to receive the internal threads of a filler cap 20. An insulating washer 21 is held in place on the outer end of the tube 12 by the cap 20. A slotted nut 22 is threaded onto the inner end 23 of the tube 17 and is forced tight against 25 the washer 21 for holding the generator in position on the outer end of the tube 12.

The filler cap 20 is formed with an axial opening 20' of a diameter greater than the generator tube 17 and a second insulating washer 24 is 30 held in place on the generator tube 17 by means of a nut 27, which is welded or otherwise secured to the tube so as to obtain an air tight connection. The tube 17 is threaded into a combustion tube 26. The outer surfaces of the inner 35 end of the combustion tube and the inner surfaces of the tube 17 are threaded for increasing the heat conducting area. The inner threaded surface of the tube 17 aids in maintaining the portion 16 of the wick in position.

40 The outer free end of the tube 17 is counterbored as shown at 30, to receive a disk 31 which is rolled into place so that it will have an airtight fit in the counterbored groove 30. The center of said disk is provided with an orifice

45 32 from which fuel vapors issue for maintaining combustion in the chamber in the tube 26. In this connection it is important to note that the wick portion 16 stops inwardly a substantial 50 distance from the outer end of the generator tube 17 forming a vapor expansion chamber 25 and that the lower portion of the combustion tube 26 extends inwardly beyond the chamber 25.

The combustion tube 26 has a plurality of ports 55 33 properly arranged for supplying air in regu-

lated proportions to said tube to maintain combustion.

A friction hinge 35 (Figure 3) connects a primer tank 36 with the fuel tank 10. The hinge consists of a pair of parallel bars 37 which have the opposite ends pivotally mounted on pins 38 carried by journals 39 and 40 at the ends of respective curved brackets 41 and 42. The bracket 41 is secured to the tank 10 adjacent the upper end while the bracket 42 is secured to an intermediate portion of the tank 35. Each pivot pin has heads 43 at the opposite ends thereof for frictionally pressing the ends of the bars against the ends of the bearings.

A modified form of hinge is shown at 45 in Figure 4, in which journals 46 and 47 are connected to the respective tanks 10 and 36. Pins 48 in the journals form pivots for a pair of parallel bars 49. Heads 50 on the opposite ends of said pins press against the bars for holding said bars frictionally in position and likewise the tank 36.

The primer tank 36 (Figure 2) has its upper open end externally threaded to receive an internally threaded filler cap 51. An insulating washer 52 is pressed upon the upper free end of the tank 36 by the cap 51. An orifice in a closure 51-a is closed by a plug 53 threaded into said orifice. A pin 54 carried by the plug 53 projects into the upper end of the closure 51-a adjacent the upper end of a priming wick which terminates in said closure. The pin or wire 54 is employed for cleaning the orifices when they become choked with carbon.

The wick 55 is held in place in the tank 36 by an internally threaded sleeve 60 upon which a closure 51-a is threaded. The sleeve projects downwardly for a short distance into the tank 36, while the outer threaded portion 61 of the sleeve extends above the cap. The lower end of the closure is seated upon the top of the filler cap 51.

The operation of my device is as follows: The tank 10 is placed in a vertical or upright position and the cap 20 together with the attached generator 17. The combustion tube 26 and the wick 15 is removed as a unit and the tank is filled with fuel. The cap is then replaced together with the wick 15 since said wick is carried by the cap and tube 17.

The primer tank 36 is moved to a vertical position and is supported in this position by the friction hinge 35 from the tank 10. The filling cap 51 is removed together with the wick 55 and the tank 36 is supplied with fuel. The wick and cap are then replaced.

The closure 51-a is unscrewed and the outer end of the wick 55 is ignited by a suitable means. The tank 36 is adjusted so that the flame 65 will play upon the threaded portion of the combustion tube 26 for causing the tube 17 to generate vapors which expand into the chamber 25 and pass through the orifice 32 at the outer end of the tube 17. These vapors are ignited by the flame 65 which is extinguished after the torch is operating properly.

The heat from the flame 66 maintains the combustion tube 26 and the generator tube 17 at the proper temperatures so vapors will be supplied to the air drawn through the ports 33 to maintain the flame 66 at all times. The threads on the interior and exterior of the tubes 17 and 26 will increase the radiating surface of said tubes.

The washers 21 and 24 being formed of insulating materials will aid in preventing too great a

rise in the temperature of the member 12 and the tank 10. If, however, the tank 10 becomes too hot for handling after long use of the torch, the tank 36 may be employed as a handle and the friction hinge 35 will retain the tank 10 in a predetermined position relative to the tank 36.

Referring more particularly to Figure 6, it will be seen that the combustion tube 26 has been removed from the generator tube 17 so that a double-duty torch is acquired. At this time the flame 65 is maintained throughout the time that the flame 65-a is used and the tank 36 is adjusted by the hinge 35 so that the flame 65 will play on the outer end of the tube 17.

It will be seen that by this construction a steady and intense flame 66 will be maintained during the operation of the torch. In view of the particular arrangement of the cap 20, washers 21, 24 and nuts 22 and 27 of the generator 17, the torch will not leak during operation thereof. When the tank 10 is filled to a pre-determined height the inner end of the tube 12 will prevent fuel from entering said tube when the tank is in a horizontal position, and when full pressure has developed in the fuel tank, the torch will operate in any position.

I claim:

1. A blow torch comprising a fuel tank, a priming tank, means connecting the tanks together for adjustably positioning the priming tank relative to the fuel tank, a wick tube communicating with and extending from the fuel tank, an internally and externally threaded generator tube having one end extending into the wick tube and the other or outer end provided with a vapor discharge orifice, a filler cap threaded onto the outer end of the wick tube having an axial, opening, the generator tube being disposed through said opening in axial alignment with the wick tube, insulating washers at opposite faces of the cap, nuts threaded on the generator tube and forcing the washers against the opposite faces of the filler cap, an internally and externally threaded combustion tube screwed on the generator tube and having a portion provided with air ports, a wick having one end held in the generator tube by the internal threads therein and extending from said tube into the fuel tank, and a wick in the priming tank for producing a flame in the combustion tube.

2. A blow torch comprising a fuel tank, a wick tube projecting from and in communication with said tank, a filler cap on the free end of the wick tube and having an axial opening, an externally and internally threaded generator tube for producing fuel vapors extended through the opening and having one end projecting into the wick tube, said generator tube being of a diameter less than the opening of the filler cap, a combustion tube having one end threaded onto the other end of the generator tube, the other end of the combustion tube being provided with air ports, the outer end of the generator tube having a vapor discharge orifice, a wick disposed in the generator tube stopping inwardly of the discharge orifice forming a vapor expansion chamber, the wick also being disposed in the wick tube and the tank and having a portion held in place by the internal threads of the generator tube, said generator tube, combustion tube, cap and wick being removable as a unit from the tank, and a lamp connected to the tank for playing a flame on the generator tube and for

igniting vapors issuing from the generator tube.

3. A blow torch comprising a fuel tank, a wick tube projecting from and in communication with said tank, a filler cap on the free end of the wick tube and having an axial opening, an externally and internally threaded generator tube for producing fuel vapors disposed through the opening and spaced therefrom and having one end projecting into the wick tube, a combustion tube having one end threaded onto the other end of the generator tube, the other end of the combustion tube being provided with air ports, the outer end of the generator tube having a vapor discharge orifice, a wick disposed in the generator tube stopping inwardly of the vapor discharge orifice to define an expansion chamber, the wick also being disposed in the wick tube and the tank and having a portion held in place by the internal threads of the generator tube, said combustion tube being removable from the generator tube so that the generator tube at the orifice will produce an intense pencil-like flame after the generator tube has been heated and the vapors exuding from the orifice are ignited, and a lamp connected to the tank for playing a flame on the generator tube and for

igniting vapors issuing from the generator tube.

4. A blow torch comprising a fuel tank, a priming tank, a fuel vapor-generator communicating with the fuel tank and a combustion tube having a portion embracing the generator with the remaining portion of said tube extending outwardly from the generator, said priming tank having means for producing a flame for igniting the vapors in the combustion tube, and a friction hinge connecting the tanks together whereby the flame from said priming tank may be directed at any point along the combustion tube.
